UNITED STATES PATENT OFFICE.

JOSEPH M. BRIGGS, OF EAU CLAIRE, WISCONSIN, ASSIGNOR OF ONE-HALF
TO ALBERT F. SCHWAHN, OF SAME PLACE.

SAUSAGE-MEAT CUTTER.

SPECIFICATION forming part of Letters Patent No. 423,899, dated March 25, 1890.

Application filed March 9, 1889. Serial No. 302,636. (No model.)

To all whom it may concern:

Be it known that I, JOSEPH M. BRIGGS, of Eau Claire, in the county of Eau Claire, and in the State of Wisconsin, have invented certain new and useful Improvements in Sausage-Meat Cutters; and I do hereby declare that the following is a full, clear, and exact description thereof, reference being had to the accompanying drawings, in which—

10 Figure 1 shows my sausage-meat cutter in perspective; Fig. 2, an enlarged view of the same in side elevation on an enlarged scale; Fig. 3, a detail view of the same in front elevation; Fig. 4, a detail sectional view on line $x x$ of Fig. 3; Fig. 5, a similar view with the section on line $y y$ of Fig. 3; Fig. 6, a transverse vertical sectional view of one of the adjustable supports for the rollers, upon which the block is supported; and Fig. 7, a vertical 20 sectional view of such support, with the plane of section at right angles to that of the section in Fig. 6.

Letters of like name and kind refer to like parts in each of the figures.

25 The object of my invention is to provide an improved sausage-meat cutter; and to this end my invention consists in the machine and in the construction, arrangement, and combination of the parts thereof, as herein-after specified.

It is intended by me to provide a machine which can be driven by power or by hand, and which shall when operated automatically turn the block upon which the material is 35 being cut so that the knives shall at each stroke strike such material at a different angle.

As shown, my machine is of the rocking-knife variety, and in it, as will appear from 40 the description hereinafter made, I employ the weight of the knives themselves or knife-carrying frame to actuate certain block-turning devices, so as to turn the block a certain distance as the knife-frame reaches either end 45 of its rocking motion.

In the drawings, A designates the block upon which the meat is to be cut, and which can be of any desired size or material. As shown, it is in the shape of an upright cylinder, whose upper end affords a horizontal ta-

ble for the cutting operation. About midway of its height it has an annular rib or flange A', which, as the block revolves, passes above the shoulders $a a$ on the upright posts or standards B B, arranged in pairs on diametrically-opposite sides of the block. Such posts standing close to the front and rear sides of the block would serve to guide and steady it if it should tend to work out of position in its rotation. This, however, with 55 the means which I use for supporting it in its rotation, it is not liable to do.

At four equidistant points below the lower end of the block near its outer edge are the supports or standards C C, preferably of cast-iron. Each one of these has, as shown, a vertical slot or way C', whose inner and outer sides are parallel to each other and in planes at right angles to a radius of the circular bottom of the block A. Held and guided in this 65 way, so as to be capable of being moved vertically up and down, but not to one side or the other of the standard, is a slide, preferably formed of the two upright parallel plates C² C², connected by the upper and lower distance 70 pieces or blocks C³ C⁴, the former at some distance from the upper ends of the plates while the latter issituated at and between their lower ends. Both these plates and blocks or distance-pieces I prefer to make of iron or other metal. 75

Journalled in the upper ends of the plates C² C² are the ends of the shaft C⁵ of a roller C⁶, such shaft extending in the direction parallel to a radius of the block-bottom. Upon the four rollers thus supported in the slides 85 in the four standards or uprights C C rests an annular bearing-plate A², fastened to or formed upon the bottom of the block.

In order that the rollers may be adjusted to support the block-bottom precisely in a horizontal position or to raise or lower the block, each of the roller-carrying slides is provided with the set-screws c c, preferably two in number, tapped down through the lower block C⁴ and bearing against the bottom of the slot or 90 way C' in the respective standard or support C.

On the block A, around the outer edge of its bottom, there is a series of gear-teeth a' a' adapted to mesh with the pinions D D at the front and back sides of the block, respectively. 100

These pinions are fixed upon horizontal shafts D'D', journaled in suitable supporting-bearings D²D². While diametrically opposite each other with reference to the block-bottom, these 5 shafts extend outward radially with reference to the block. Upon the outer end of each shaft is fixed a ratchet-wheel E, the teeth of the two wheels being turned in opposite directions, so that as turned by pawls engaging 10 their teeth the wheels will both cause their connected pinions to turn the block in the same direction, as will be clearly understood from the drawings.

Pivoted upon each shaft D', between the 15 ratchet-wheel thereon and the shaft-bearing, is a rocking frame or lever F, provided with the ratchet-engaging pawls f'f, preferably two in number, though one or more can be used, as desired, without departure from my invention. 20 Each lever is weighted so that it tends to turn or swing in a direction to cause the pawls to ride over the inclined sides of the ratchet-teeth. Pivotedly connected with the lighter or unweighted end of the lever is a 25 rod G, which at its upper end is connected with a step H, hinged to a suitable support close to the side of the block A and extending across at right angles to a diameter of the top of the block. The two hinged steps 30 are diametrically opposite to each other, with the axes of their swing on their hinges at right angles to the same diameter of the block top. I prefer to make the upper sides of these steps slightly concave and to set into 35 them blocks or strips of hard wood, for a purpose which will be set forth more at length hereinafter. Each pawl-carrying lever or frame F is so weighted as to normally hold the respective step swung upward, as shown 40 best in Fig. 2, and to return it to its elevated position when it has been depressed. The connection between each rod G and the respective step is preferably such as shown in Figs. 2 and 3, consisting of an eye g on the rod engaging an eye or loop h on the step, so that 45 the step and rod must always move together, while the rod is free to swing with reference to the step as its lower end moves with the weighted pawl-carrying frame or lever. If 50 desired, a spring can be used instead of a weight to return each pawl-frame and the rod-connected step to their normal positions.

The cutter which I use is, as indicated hereinbefore, of the rocking kind, adapted to 55 rest and rock upon the top of block A. It consists of the parallel cutter-blades I, having their lower cutting-edges curved on the arc of a circle in vertical planes, held together in a frame to which is given, by means to be 60 described, a rocking motion, so as to rock the curved edges of the knives across the block. This frame can be of any desired construction and material, while I prefer to make it in the shape shown, of cast-iron.

65 From a cross-bar I', extending across above the knives in line with the centers from which the knife-edges are curved, arms I², one for

each cutter, extend downward to the middle points of the cutters and are there attached to the latter by a bolt i, passing through the 70 arm ends and the cutter-blades. Upon this bolt between the cutter-blades I place collars or sleeves i' i'', forming distance-pieces to hold the blades apart upon the bolt. From opposite sides of the cross-bar I' other arms 75 I² extend downward and outward and at their lower ends are attached to the outer ends of the cutter-blades by bolts i² i², which, like bolt i, pass through the arm ends and the blades, and between the blades are provided with distance-pieces to hold the knives in place on the bolts. With this construction the knives are held firmly upright and parallel to each other with their curved edges in the same 80 curved plane.

85 As shown in the drawings, the upper ends of the bars I² I² are attached to plates which are bolted to opposite sides of the cross-bar; but I do not limit myself to such construction.

The cutter is so situated as, while resting on 90 the block, to be capable of a rocking motion diametrically across the same in the direction of the two opposite steps H H. The knives are of such length that when the cutter is rocked to its limit toward either side of the 95 block the ends of the knife-blades will rest upon the step at that side. The weight of the cutter-frame will then, while the frame is so rocked, be brought to bear upon the step to force the same down. The downward movement of the step caused by such weight will, through the connecting-rod G, swing the pawl-carrying lever F to cause the pawls to turn the respective ratchet-wheel so as to rotate the block A a certain distance. The ends of the 100 knives, where they are to bear upon the steps, are made flat and without cutting-edges, which would cut or wear away the steps. The blocks or strips of hard wood, which, as indicated hereinbefore, I intend to set into the upper 105 surfaces of the steps, are to resist wearing away by any friction or blow of the knife ends.

To give the cutter its desired rocking movements, I provide a shaft K, journaled in a 115 suitable frame or standard K'. Upon opposite ends of this shaft are the crank-wheel K², for turning the shaft, and a larger wheel K³, connected with the cross-bar I² of the cutter-frame by a pitman-rod connection, so that 120 at each rotation of the shaft the cutter-frame will be rocked to the opposite limit of its motion to bring the cutters clear of the block and upon first one step and then the other.

In order to provide for adjustment of the 125 swing or throw of the cutter, I do not connect the end of the pitman or connecting rod L directly with the cross-bar I' of the cutter-frame, but with a piece M, adjustably attached to the middle of such cross-bar, so as to be capable of adjustment in the direction of a 130 diameter of the circle upon which the curve of the knife-edges is struck—that is, it is made adjustable at right angles to the cross-bar in

a plane equidistant from the opposite ends of the knife-blades. As shown, it consists of the two parallel plates, each having a vertical slot m to embrace the cross-bar I' . The bolt or pin M' , upon which the end of the connecting-rod L is pivoted, extends across between the upper ends of the plates. The lower ends of the plates are connected by a block M^2 , which holds them at a certain distance apart.

5 Through such block or plate is tapped the screw M^3 , engaging with its upper end the cross-bar I' . This screw serves to adjust the piece with reference to the bar, while set-screws $m' m'$, passing through the sides of the 15 plates, engage the cross-bar, so as to fasten the piece at any adjustment.

In order to provide for change of throw of the swinging pawl-carrying frame or lever, the rod is made in two parts, as shown in Figs. 20 2 and 3, with the upper part screwed into the lower. A shortening or lengthening of this rod will cause the respective step connected with its upper end to stand lower or higher when the pawl-frame or lever is in its normal 25 position, so that the cutter in pressing the step down to its bearing upon the tops of the uprights $B B$ will move the step and consequently the pawl-frame a less or greater distance. I prefer to have the upper ends of the 30 standards $B B$ so situated as to act as stops to engage the step when it has been swung down into a horizontal position, but do not limit myself to such construction, as stop pins or lugs on the frame can be provided for

35 the same purpose. With the rods $G G$ made adjustable in length the necessary raising of the shafts carrying the pinions $D D$ and ratchet-wheels $E E$ as the block is raised by the adjustment of the supporting-wheels, as set 40 forth hereinbefore, can be compensated for.

The operation of my machine is briefly as follows: With the cutter rocked by rotation of the driving-wheel K^3 over into one of the 45 positions shown in dotted lines in Fig. 2 the top of the block A is left clear and the meat to be cut is placed upon it. The shaft K and wheel K^3 are then turned by means of the crank-wheel K^2 , driven by power or by hand. As the cutter is by the connecting-rod rocked 50 back and forth across the block and into the positions shown in dotted lines in the figure just referred to, it makes a series of cuts entirely across the material on the block-top, there being one cut for each knife as the cutter moves in either direction. As the cutter 55 rocks off of the block at the end of its movement in one direction, it bears down upon the step toward which it has been rocking. While thus bearing the step down and causing the

60 pawl-carrying frame to swing and turn the ratchet-wheel E to rotate the block a certain distance, the cutter is rocked clear of the block-top, so as to leave the block free to be rotated. With the block thus turned the 65 knives will obviously, as the cutter rocks back, cut across the material on the block in a different direction with reference to the material:

than before. As the rocking of the cutter and the step-by-step turning of the block with the material thereon are kept up, the successive cuts made by the series of knives will always change in direction across the material, and the result will be that the meat can be cut evenly and quite fine, the degree of fineness desired being easily secured with but a 70 comparatively short use of the machine. As the weight of the cutter is supported by the block and the steps at different points of its motion and as its movement is an easy rocking one upon the circularly-curved knife-edges, it is obvious that but very little power will be necessary to give the cutter the motions desired. With the block turned by the weight of the cutter through the mechanism described I avoid all necessity of any power or hand 80 driven devices for rotating the block, such as have been used heretofore, with their necessary complications of gearing and liability to get out of order. The adjustable connection between the end of connecting-rod L and the 85 cross-bar H of the cutter-frame provides for an adjustment to compensate for wear of the knife-blades or their reduction in height by successive sharpenings. If it were not for this adjustment, the throw of the rocking 90 cutter would change as the cutter-blades were worn or sharpened. With the piece M made adjustable as the blades diminish in height the point of connection of the connecting-rod with the cutter can be correspondingly 95 raised.

In order that the shafts $D' D'$, carrying the pinions $D D$ and ratchet-wheels $E E$, may be adjusted to correspond with the adjustment of the block A , so that the pinions shall always be properly in gear with the teeth $a' a'$ 105 on the block-bottom, the shaft-bearings $D^2 D^2$ are to be made vertically adjustable, as by fastening them to adjustable supports. One form of such supports which can be used 110 is shown in the drawings. It consists of a plate or bar D^3 , to which the respective journal box or bearing D^2 is attached. Through such plate at its four corners pass the upright screws $D^4 D^4 D^4 D^4$, one at each corner. 115 Upon each of such screws, which at their lower ends are fixed to or set in a base D^5 , are the two nuts $D^6 D^6$, one above and one below the plate or bar D^3 . These nuts when screwed against the opposite faces of the 120 plate or bar will clamp it between them, so as to hold it securely and firmly. The adjustment of the plate to any desired height can 125 obviously be secured by turning the nuts to raise or lower them on their respective screws. The adjustment of the shafts can, as indicated hereinbefore, be compensated for by adjustment of the lengths of the rods or bars G , connecting the steps $H H$ with the respective pawl-carrying frames $F F$, so that 130 the desired regular amount of feed or turning of the block can be secured.

As shown in the drawings, the cutter has four knives; but I do not limit myself to that

or any other number. More knives can be used; but the number should always be an even one.

Having thus described my invention, what I claim is—

1. In combination with the rotary block or table and the rocking cutter thereon adapted to be rocked across it, a movable piece at one side of the block upon which the cutter rocks at one end of its motion, and suitable gearing operated by such piece connected with the rotary block, so as to turn the same.
2. In combination with the rotary block or table and the rocking cutter thereon, movable pieces at opposite sides of the block engaged by the cutter as it rocks off of the block at such sides at the ends of its motion, and suitable gearing for turning the block connected with such pieces and with the rotary block, so as to turn the latter, substantially as and for the purpose specified.
3. In combination with the rotary block or table and the rocking cutter thereon, the hinged steps at opposite sides of the block upon which the cutter rocks at opposite ends of its travel, pawl-and-ratchet devices connected with the hinged steps, and connecting gearing between such devices and the rotary block or table, substantially as and for the purpose shown.
4. In combination with the rotary table or block and a movable step at one side thereof, a pawl-carrying lever connected with the step, so as to operate thereby, a ratchet-wheel, a pinion connected therewith, so as to be turned by it, gear-teeth carried by the block meshing with such pinion, and the rocking cutter on the block, substantially as and for the purpose set forth.
5. In combination with the rotary block and the rocking cutter thereon, the hinged steps at opposite sides of the block in the track of the cutter, the weighted levers connected with the respective steps and carrying one or more pawls, a ratchet-wheel for each lever, a pinion connected with each ratchet-wheel, and gear-teeth on the block meshing with these pinions, substantially as and for the purpose described.
6. In combination with the rotary block, the means for rotating the same, consisting of a

pivoted step, a weighted lever, a connecting-rod made adjustable in length connecting the step therewith, one or more pawls on the lever, a ratchet-wheel, a pinion connected therewith, so as to be rotated by it, and gear-teeth on the block, substantially as and for the purpose specified.

7. In combination with the rotary block, the means for rotating the same with a step-by-step motion, which consists in a hinged step, a weighted lever, the rod connecting the step and lever made in two parts, with one part screwed into the other, one or more pawls on the lever, a ratchet-wheel and pinion connected together, and gear-teeth on the block, substantially as and for the purpose shown.

8. In a sausage-meat cutter, in combination with the rotary block, the rollers supporting the same, so as to leave it free to rotate on a vertical axis, and separate and independent means for adjusting the height of each of the rollers, substantially as and for the purpose set forth.

9. In a sausage-meat cutter, in combination with the rotary block, the rollers for supporting the same and allowing it to rotate, having bearings made vertically adjustable, the hinged steps at opposite sides of the blocks, the weighted levers, the connecting-rods connecting the levers with the respective steps made adjustable in length, one or more pawls on each lever, a ratchet-wheel for each lever, a pinion connected with each ratchet-wheel, so as to rotate therewith, and gear-teeth on the block meshing with the pinions, substantially as and for the purpose set forth.

10. In combination with the rotary block of a sausage-cutting machine adjustably supported, one or more feed devices for rotating the block, each supported upon a plate or bar, screws for supporting such bar, and nuts on each of such screws above and below the bar, substantially as and for the purpose shown.

In testimony that I claim the foregoing I have hereunto set my hand this 2d day of February, A. D. 1889.

JOSEPH M. BRIGGS.
